CARRIER FOR BOTTLES OR THE LIKE

George E. Thiery, Levittown, Edward H. Werner, North Massapequa, and Edward L. Tarantino, Huntington, N.Y., assignors to Kitco Corporation, Hicksville, N.Y., a corporation of New York

Filed May 20, 1960, Ser. No. 60,669

Term of patent 14 years

(Cl. D58—26)

FIG. 1 is a perspective view taken from the top, one side and one end of a carrier for bottles or the like, showing our new design;

FIG. 2 is an elevational view of the side opposite the side shown in FIG. 1,

FIG. 3 is an elevational view of the end opposite the end shown in FIG. 1, and

FIG. 4 is a bottom plan view thereof.

We claim:

The ornamental design for a carrier for bottles or the like, substantially as shown.
